UNITED STATES PATENT OFFICE

MARSDEN C. HUTTO, OF DETROIT, MICHIGAN, ASSIGNOR TO HUTTO ENGINEERING COMPANY, INC., A CORPORATION OF MICHIGAN

DEVICE FOR GRINDING EXTERNAL CYLINDRICAL SURFACES

Application filed July 11, 1928. Serial No. 291,784.

This invention relates to a grinding device and more particularly to a device of this character for grinding, polishing or similarly treating the external cylindrical surfaces of 5 shafts, cranks, rods, cylinders and the like.

It is the object of this invention to provide an apparatus of simple, durable and efficient construction whereby such work may be done thoroughly, accurately and expeditiously with a minimum expenditure of power and which can be adjusted with ease and facility so as to adapt the tool to the work in hand and permit of taking up wear as the operation of the tool progresses.

15 In the accompanying drawings:

Figure 1 is a longitudinal section showing one embodiment of my improvements.

Figure 2 is an end elevation of the same.

Figure 3 is a cross section taken on line 20 3—3 Fig. 1.

Figure 4 is a fragmentary longitudinal section taken on line 4—4 Fig. 3.

Figure 5 is a longitudinal section of another form of grinding device containing my 25 invention.

Figure 6 is a fragmentary end elevation of the same.

Figures 7 and 8 are transverse sections taken on the correspondingly numbered lines 30 in Fig. 5.

Figure 9 is a fragmentary horizontal section taken on line 9—9 Fig. 5.

In the following description, similar characters of reference indicate like parts in the 35 several figures of the drawings.

The form of grinding device illustrated in Figs. 1, 2, 3 and 4 is constructed as follows:

The numeral 10 represents the body of the tool which is preferably of tubular form and 40 made of metal of any suitable character, and the member or article 11 which is adapted to be ground on its outer cylindrical surface or periphery by means of this tool is adapted 45 to be received lengthwise within the bore or longitudinal opening of the body. The member to be ground may either be a shaft, crank or other object which has an external cylindrical surface adapted to be operated upon, 50 and in the present case this member is repre-

sented by dotted lines as shown in Figs. 2 and 3.

Within the bore of this body is arranged a plurality of abrasive members which are adapted to engage with the periphery of the 55 article to be ground or treated, these abrasive members being arranged in an annular row and preferably equidistant around the axis of the body.

Although these abrasive members may be 60 variously constructed each of the same, as shown in the drawings, preferably consist of a channel shaped holder 12 arranged lengthwise of the body and preferably equal in length and flush with the opposite ends 65 of the same, and an abrasive surface arranged on the inner side of the holder and consisting preferably of a longitudinal stick or stone 13 of carborundum or other suitable abrasive material, which is secured in 70 the inner side of the channel shaped holder in any approved manner.

Each of these abrasive holders is guided on the body of the tool so as to be capable of radial movement thereon toward and from 75 the axis of the tool and thereby permit the abrasive inner surface of the holder to be expanded or contracted to suit the diameter of the cylindrical surface which is to be ground.

Various means may be employed for thus 80 guiding the abrasive member on the body, but in the construction shown in Figs. 1, 2 and 3, this is accomplished by means of longitudinal radial guide grooves 14 formed in the bore of the body and adapted to receive 85 one of the abrasive holders between the ends thereof, and two guide rings 15 seated in annular rabbets 16 at opposite ends of the body and detachably secured therein by means of screws, the shanks 17 of which pass through 90 openings in these guide rings and tap into the adjacent parts of the body while the heads 18 bear against the outer sides of these rings, each of these rings being provided on its inner edge with a plurality of radial guide 95 ways or slots 19 which receive the adjacent end portions of the respective abrasive holders, as best shown in Figs. 1 and 2.

By selecting a pair of guide rings of the right size from a set having different inter- 100

nal diameters it is possible to guide the end portions of the several stone holders and firmly support the same for grinding cylindrical objects which are of different diameters and still utilize the same supporting body 10 and the other parts of the tool which are associated therewith. In addition to radially guiding these abrasive members on the body by means of the grooves 14 in the body and the grooves 19 in the guide rings 15, each of the abrasive members may be further guided in its radial movement toward and from the axis of the tool by means of guide pins 20 secured at their inner ends to the outer side 15 of the respective holder adjacent to opposite ends thereof and projecting radially outward through guide openings 21 in the adjacent part of the body 10, as shown in Fig. 1.

These guide pins 20 are fitted somewhat loosely in the guide openings 21 so as to not only permit the abrasive member to move radially on the body, but also to tilt a limited extent relative to the axis thereof in order to permit the abrasive inner surfaces of the 25 holders to adapt themselves to any irregularities of the cylindrical surface to be ground which may be out of round or parallel, and thereby enable the several abrasive members to gradually grind down the cylindrical surface which may be out of true until the same 30 is perfectly cylindrical.

Means are provided for adjusting the working diameter of the tool which cooperate with the abrasive members so as to positively 35 and rigidly hold the same against expansion during the grinding operation and still permit them to rock so that they can adapt themselves to any irregularities on the surface of the object which is being ground.

40 In the construction shown in Figs. 1-3 this is accomplished by means which comprise two oppositely disposed internal cones 22, 23 which are preferably constructed in the form of rings and arranged around opposite ends 45 of the body 10 and engage respectively with the guide pins 20 at opposite ends of the abrasive members. Upon moving these cones lengthwise of the axis of the tool in one direction the abrasive members are forced inwardly due to the wedge action of these cones 50 against the outer ends of the guide pins 20 and thereby contract the working diameter of the tool, while upon moving these cones in the opposite direction lengthwise of the 55 axis of the tool the abrasive members are permitted to expand and thereby increase the working diameter of the tool.

In the construction shown in Fig. 1 the conical surfaces of the two cones flare inwardly or toward each other, and the adjustment of the same relatively to one another lengthwise of the tool is effected by means of a casing or shell 24, one end of which is rigidly connected with the cone 22 and preferably 65 formed integrally therewith while the other

cone 23 is slidable lengthwise within the opposite end of this casing, and an adjusting sleeve or ring 25 engaging with the outer end of the last-mentioned cone and having a screw connection 26 with the adjacent part of the 70 casing 24.

Upon tightening the screw sleeve 25 on the casing 24, the two cones 22, 23 are moved toward each other lengthwise of the axis of the tool whereby the wedge action of these cones 75 on the outer ends of the guide pins 20 will cause the abrasive members to be moved radially inward and thereby reduce the working diameter of the tool, while upon unscrewing the sleeve 25 from the casing the cones are 80 permitted to spread lengthwise of the tool and thereby enable the abrasive members to move radially outward and increase the working diameter of the tool accordingly.

To facilitate the turning of the adjusting 85 sleeve 25 the same is provided with a longitudinal extension 27, the periphery of which is provided with a plurality of openings 28 adapted to receive a wrench or other tool for turning this sleeve in the desired direction. 90

The longitudinal movement of the cones in the direction for causing them to spread and permit the working diameter of the tool to be increased is preferably effected by resilient means which in the present case consist of springs 70, preferably three in number, arranged in an annular row in the space between the body 10 and the cone casing 24 and each interposed between the inner opposing ends of the cones, and a retaining or longitudinal guide rod 71 upon which each spring 70 is mounted and one end of which is secured to the cone 22 while the other end thereof slides in a longitudinal opening 72 in the cone 23, as best shown in Fig. 1. 100

Upon unscrewing the sleeve 25 the two cones are spread apart lengthwise of the tool in the same measure.

The several abrasive members are yieldingly held in their outermost radial position 110 so that their guide pins 20 abut against the adjusting cones 22 and 23, this being preferably effected by two garter springs 29 arranged adjacent to opposite ends of the supporting body 10 and the abrasive members, 115 and each of these springs being engaged with the outer sides of the heads 15 of the screws whereby the guide rings are secured to the body and with the inner sides of retaining lugs or projections 30 arranged at the corresponding ends of the holders of the abrasive members. 120

The screw heads 15 are provided on the periphery of the same with annular grooves 31 in which the adjacent parts of each expansion 125 spring 29 is seated and the projections 30 are preferably constructed in the form of hooks so that when these springs engage with the screw heads 15 and hooks 30 the same are prevented from becoming detached from these 130

members. Inasmuch as the screw heads 15 and the retaining lugs 30 of the abrasive members alternate with each other and are arranged on concentric circles of different diameters, each of the springs 29 is deflected at intervals throughout the circumference thereof and thereby provides a resilient action which constantly tends to move the abrasive members outwardly to the fullest extent permissible by the position of the cones 22 and 23.

Means are provided for permitting the cones to move lengthwise relative to the body of the tool but preventing these cones and the body from turning circumferentially relatively to each other. In the preferred construction these means consist of one or more retaining pins 32, preferably three, arranged equidistant around the body of the tool and 20 each provided at its inner end with a screw threaded shank 33 secured in a threaded opening in the adjacent part of the body, while its outer part projects radially outward through a longitudinal slot 34 in the adjacent 25 part of the cone 23 and a longitudinal slot 35 in the casing 24 which is connected with the other cone 22. Obviously these retaining pins operate as keys or splines which permit the cones to be moved freely lengthwise relative 30 to each other and also relative to the body 10 of the tool for adjusting the abrasive members to the desired diameter of the working surface, and also permit the abrasive members to tilt in adapting themselves to any out 35 of true cylindrical condition of the surface which is being ground, while at the same time preventing these cones and the supporting body 10 from turning circumferentially one relatively to the other.

40 Means are provided for supporting the body 10 of the tool so as to permit the same to tilt relative to the axis of the object which is being ground and thereby compensate for any variation in the axial alignment of the 45 abrasive members relatively to the axis of the work piece which is being ground. Although the means for thus supporting the body of the tool may be variously constructed the form which is shown in the drawings is 50 satisfactory and constructed as follows:—

The numeral 36 represents a swivel ring which surrounds the central part of the annular casing 24 upon which the cones are mounted, which ring is rigidly connected 55 with the body 10 so as to move in unison therewith, this being preferably accomplished by providing this ring with countersunk openings 37 which receive the outer headed ends 38 of the retaining pins 32 so 60 that the latter in effect form the double function of screws for connecting the swivel ring 36 with the body and also as keys or splines which hold the cones against turning on the body, but permit the cones to move lengthwise thereon. The swivel ring 36 is arranged

within an opening of a supporting bracket 39, the joint between the periphery of this ring and the bore of the bracket 39 being preferably so constructed that this ring together with the parts mounted thereon is capable of 70 rocking within the bracket transversely of the axis of the tool.

This is preferably accomplished by providing the periphery of the swivel ring with a convex spherical surface 40 and engaging the 75 same with a concave surface in the bore of the supporting bracket 39. This concave surface in the supporting ring preferably consists of two cones 41, 42 which flare inwardly toward each other from opposite sides of the 80 bracket 39.

The conical surface 41 is preferably formed on an integral part of the bracket 39, while the other conical surface 42 is formed on a section 43 of the bracket which is detachably connected by means of screws 44 with the main part of this bracket, as shown in Fig. 1. By this means the bracket 39 is provided in effect with a concave socket which is engaged by the convex surface 40 of the swivel ring which operates to permit the tool to rock on the bracket due to the swivel joint between the swivel ring and the bracket, but holds the body and the parts associated therewith against lengthwise 95 movement on the bracket.

Rotation of the grinder body 10 and parts associated therewith relative to the bracket is prevented by a retaining pin 45 secured to the bracket and engaging with a longitudinal groove 46 formed in the periphery of the 100 swivel ring 36.

The extent of the rocking or floating movement of the tool body 10 and the parts associated therewith is limited by means of a 105 limiting pin 47 mounted by means of a screw joint 48 on a part of the bracket body and engaging with a longitudinal groove 49 in the swivel ring, the opposite ends 50 of this last-mentioned groove forming stops which are adapted to engage with opposite sides of the stop or limiting pin 47 and thereby arrest the swivel ring when the same has reached a predetermined position upon rocking in either direction from its central or 110 neutral position.

In using this tool the same may be mounted so that the abrasive members are incapable of rotary motion, but are only capable of radial movement toward and from the axis of the tool and also rocking relatively thereto, in which case the cylindrical object of which the periphery is to be ground is rotated while in engagement with the abrasive faces of the 120 abrasive members, and this object is also reciprocated lengthwise of the axis of the tool so that by this combined rotary and longitudinal movement of the object the requisite 125 grinding of its periphery is accomplished by 130

engagement of the same with the abrasive members.

The tool shown in Figs. 1, 2, 3, 4 is more particularly designed for use in this manner and for this purpose the bracket 39 is provided at its lower end with a foot or base 51 whereby this tool may be attached to a suitable stationary part on the machine, which latter is provided with means for gripping the work piece and rotating as well as reciprocating the same lengthwise relatively to the axis of the grinding tool.

Obviously, however, the work piece may be held stationary and the bracket 39 upon which the tool is mounted may be rotated and also reciprocated lengthwise of the axis of the work piece for the purpose of grinding the cylindrical peripheral surface of the work piece to the requisite extent, this manner of using the tool being a mere reversal of that previously described. The same effect is produced if the grinding tool is rotated and the working piece reciprocated lengthwise, or vice versa.

In using the tool in any of the ways just described the abrasive members are set up so as to fit the surface to be ground on the work piece by moving the adjusting cones 22 and 23 relatively to each other the requisite extent for this purpose. When the tool has been thus adjusted the abrasive members will be held positively in this position and prevented from radially moving outward so that upon rotating the work piece and the stones one relatively to the other, the grinding action of the stones upon the work piece will be produced circumferentially of the latter, and upon moving the work piece and the tool lengthwise one relatively to the other this traversing action will cause the grinding effect on the work piece to be extended lengthwise over the work piece corresponding to the longitudinal stroke of the work piece and tool relatively to one another.

When the grinding has proceeded sufficiently to cause the stones to free themselves from the surface of the work piece, then the adjusting sleeve 25 is again tightened so as to draw the cones 22, 23 together and thereby by push the abrasive members inwardly for again bringing them in close working contact with the work piece, this operation of tightening and then operating the tool until it is again free being repeated continuously until the desired amount of grinding or polishing on the work piece has been accomplished. During this grinding operation of the abrading members the adjusting cones operate as a floating adjusting device which permits the cones to automatically move lengthwise of the tool in one direction or the other under the pressure of the abrasive members and thereby enable one end of the abrasive members to project inwardly toward the axis of the tool to a greater extent

than the opposite ends of the same so that these abrasive members can adapt themselves during the initial portion of the grinding operation to any out of true condition of the cylinder surface of the work piece. As the 70 grinding of such an out of true work piece proceeds the abrasive members gradually true up this irregularity in the work piece and ultimately grind the same into true cylinder form during which operation the cones automatically shift their position as a unit 75 relatively to the axis of the tool and adapt themselves to the gradually straightening position of the abrasive members until the latter finally assume a position in which their faces are parallel with the axis of the tool and complete the grinding operation while thus arranged.

It is therefore possible by this means to produce a perfectly cylindrical periphery or external surface on a work piece such as a shaft, rod, pin, cylinder or the like of any desired diameter or length within the limits of the capacity of the machine, and to grind such external cylinder surface perfectly true and accurate throughout the entire circumference and length of the same. This can be accomplished with ease and facility and with a minimum expenditure of power, thereby 90 materially reducing the cost of doing such work as well as improving the quality of the same.

In the modified form of this grinding device shown in Figs. 5-9 the body 10a of the tool is incapable of a rocking or swivelling motion on the bracket 39a and instead is rigidly secured thereto by screws 52 connecting this bracket with an external flange 53 at one end of the body, as shown in Fig. 1. Turning of the cones relatively to the body 100 but permitting longitudinal movement of the same relatively to one another and the body is permitted by a retaining pin 54 on the flange 53 of the body engaging with a longitudinal opening 55 in the cone casing 24, and a retaining pin 56 on the cone casing engaging with a longitudinal groove 57 in the sliding cone 23.

In this modified form of my invention, operative engagement of the cones with the abrasive members is obtained by a plurality of longitudinal adjusting plates 57 arranged in an annular row around the bore of the body 10a and each arranged in a longitudinal radial slot or guideway 58 in the body, and provided with rounded ends 59 engaging with hardened guide pins 60 mounted on the body at opposite ends of the respective slot. On its inner edge each adjusting plate is provided at its ends with inwardly projecting bearing lugs 61 engaging with the outer side of the adjacent abrasive holder near opposite ends thereof, and on the outer edge of each adjusting plate at the ends thereof the same 115 is provided with outwardly projecting bear- 120

ing lugs 62 which engage respectively with the adjusting cones 22, 23.

Upon adjusting the cones 22, 23 lengthwise relative to each other the wedging effect 5 of the same is transmitted through the adjusting plates to the abrasive members which are yieldingly held in their expanded position by garter springs 29, each engaging with lugs 18a on one end of the several abrasive 10 holders 12 and lugs 15a arranged on the corresponding end of the body 10a and alternating with the holder lugs 18a.

The operation of this tool is substantially the same as that shown in Figs. 1-4 inasmuch 15 as the adjusting plates are free to rock in the slot 58 as the abrasive members tilt upon engaging an out-of-round or irregular part of the work piece and then automatically return the abrasive members to their normal 20 position in which they are parallel with the axis of the tool when the non-straight or uneven surfaces of the work piece have been ground down.

In this construction the cones also float as a 25 normally non-expansive unit as part of the adjusting mechanism for the abrasive members which positively holds the latter to their work but permits the same to tilt for overcoming irregularities, and also readily permitting of adjusting the working diameter of the abrasive members by adjusting the cones relative to each other lengthwise of the axis 30 of the tool to permit grinding articles of different diameter and also for taking up wear 35 on the abrasive members and compensating for stock removed by grinding from the surface of this work piece.

I claim as my invention:

1. A grinding device comprising a body 40 provided with a longitudinal passage for the reception of the article to be ground, a plurality of abrading members arranged in an annular row around said passage and having abrading surfaces at their inner sides adapted 45 to engage the periphery of said articles, and a controlling device cooperating with said abrading members and having parts arranged externally of said body and adjustably rigid relative to each other to positively fix the 50 general limit of expansion of said members, and spring means for yieldingly drawing said abrading members laterally outward comprising relatively movable projections arranged at opposite ends of said abrading members, 55 relatively fixed projections arranged at opposite ends of said body and alternating with the movable projections at the respective ends of the abrasive members, and springs each engaging with the projections at the corresponding 60 ends of the abrasive members and the body.

2. A grinding device for operating on external cylindrical surfaces, comprising a tubular supporting and driving body adapted 65 to receive the article to be ground, a plurality

of abrading members arranged in an annular row within said body and each extending lengthwise thereof and provided on its inner side with an abrasive surface, guide rings which are detachably mounted on opposite 70 ends of said body and interchangeable with others of different diameter, and which said abrasive members are provided with radial slots for receiving and guiding them radially relative to the axis of the tool, and means for controlling the position of said abrasive members relative to the article to be ground.

3. A grinding device for operating on external cylindrical surfaces, comprising a tubular body adapted to receive the article to be 75 ground, a plurality of abrading members arranged in an annular row within said body and each extending lengthwise thereof and provided on its inner side with an abrasive surface, guide rings which are arranged at opposite 80 ends of said body and upon which said abrasive members are guided radially relative to the axis of the tool, screws for securing said rings to said body and having relatively fixed heads, lugs arranged at opposite 85 ends of the abrasive members, springs engaging with said heads and lugs and operating to draw said abrasive members radially outward, and adjustably rigid means cooperating with said abrasive members and operating to positively limit the expansion of the 90 same.

4. A grinding device for operating on external cylindrical surfaces, comprising a tubular body, a plurality of abrasive members arranged in an annular row around the bore of said body and each having an abrasive inner surface adapted to engage the periphery of the article to be operated upon, oppositely disposed cones arranged on the exterior of 100 said body and operatively engaging with opposite ends of said abrasive members and both movable lengthwise of the axis of the tool, and means for adjusting said cones relatively to one another lengthwise of said body, including a casing one end of which is connected with one of said cones and in the other end of which the other cone is slidable lengthwise and an adjusting sleeve engaging the last-mentioned cone and having a screw 105 connection with said casing.

5. A grinding device for operating on external cylindrical surfaces, comprising a tubular body, a plurality of abrasive members arranged in an annular row around the bore of said body and each having an abrasive inner surface adapted to engage the periphery of the article to be operated upon, oppositely disposed cones arranged on the exterior of 110 said body and operatively engaging with opposite ends of said abrasive members and both movable lengthwise of the axis of the tool, means for adjusting said cones relative 115 to one another lengthwise of said body, and 120

means for causing said adjusting means to turn with said body.

6. A grinding device for operating on external cylindrical surfaces, comprising a tubular body, a plurality of abrasive members arranged in an annular row around the bore of said body and each having an abrasive inner surface adapted to engage the periphery of the article to be operated upon, oppositely disposed cones arranged on the exterior of said body and operatively engaging with opposite ends of said abrasive members and both movable lengthwise of the axis of the tool, means for adjusting said cones relatively to one another lengthwise of said body, including a casing one end of which is connected with one of said cones and in the other end of which the other cone is slideable lengthwise and an adjusting sleeve engaging the last-mentioned cone and having a screw connection with said casing, and a pin secured to said body and engaging with a longitudinal slot in said casing.

7. A grinding device for operating on external cylindrical surfaces, comprising a tubular body, a plurality of abrasive members movable radially on said body and having abrasive surfaces on their inner sides for engaging the periphery of the articles to be operated upon, and a swiveling support for said body.

8. A grinding device for operating on external cylindrical surfaces, comprising a tubular body, a plurality of abrasive members movable radially on said body and having abrasive surfaces on their inner sides for engaging the periphery of the articles to be operated upon, a supporting bracket, and a swivel member supporting said body and capable of rocking on said bracket.

9. A grinding device for operating on external cylindrical surfaces, comprising a tubular body, a plurality of abrasive members movable radially on said body and having abrasive surfaces on their inner sides for engaging the periphery of the articles to be operated upon, means for adjusting said abrasive members radially including oppositely disposed cones surrounding said body and operatively engaging said abrasive members at opposite ends thereof, a casing upon which said cones are mounted, a supporting bracket and a swivel ring mounted on the exterior of said casing and having an external spherical surface engaging with an internal spherical surface on said bracket.

10. A grinding device for operating on external cylindrical surfaces, comprising a tubular body, a plurality of abrasive members movable radially on said body and having abrasive surfaces on their inner sides for engaging the periphery of the articles to be operated upon, means for adjusting said abrasive members radially including oppositely disposed cones surrounding said body

and operatively engaging said abrasive members at opposite ends thereof, a casing upon which said cones are mounted, a supporting bracket, and a swivel ring mounted on the exterior of said casing and having an external spherical surface engaging with an internal spherical surface on said bracket, said bracket consisting of sections which form the spherical portion thereof and said sections being detachably connected with each other.

11. A grinding device for operating on external cylindrical surfaces, comprising a tubular body, a plurality of abrasive members arranged in an annular row within said body and guided thereon for radial movement relative to the axis thereof, means for adjusting said abrasive members radially including cones operatively engaging opposite ends of said abrasive members, a casing which is arranged on the exterior of said body and upon which said cones are mounted, a supporting bracket, a swivel ring interposed between said casing and bracket and pivotally mounted on the bracket, and a coupling member connected with said body and swivel ring and passing through a longitudinal slot in said casing.

12. A grinding device for operating on external cylindrical surfaces, comprising a tubular body, a plurality of abrasive members arranged in an annular row within said body and guided thereon for radial movement relative to the axis thereof, means for adjusting said abrasive members radially including cones operatively engaging opposite ends of said abrasive members, a casing which is arranged on the exterior of said body and upon which said cones are mounted, a supporting bracket, a swivel ring surrounding said casing and capable of rocking in said bracket, and means for limiting the rocking motion of said ring in said bracket.

13. A grinding device for operating on external cylindrical surfaces, comprising a tubular body, a plurality of abrasive members arranged in an annular row within said body and guided thereon for radial movement relative to the axis thereof, means for adjusting said abrasive members radially including cones operatively engaging opposite ends of said abrasive members, a casing which is arranged on the exterior of said body and upon which said cones are mounted, a supporting bracket, a swivel ring surrounding said casing and capable of rocking in said bracket, and means for limiting the rocking motion of said ring in said bracket, consisting of a limiting pin mounted on said bracket and projecting into a longitudinal groove in said swivel ring.

14. A grinding device for operating on external cylindrical surfaces, comprising a tubular body, a plurality of abrasive members arranged in an annular row within said body,

means for adjusting said abrasive members radially on the body including cones arranged on the exterior of the body and operatively engaging the opposite ends thereof, means for 5 adjustably connecting said cones and holding them rigidly in position to limit the expansion of said abrasive members, and spring means for holding said cones in their adjusted position, comprising longitudinal retaining rods each secured to one of said cones and sliding on the other cone, and springs each surrounding one of said rods and interposed between said cones.

15. A grinding device for operating on external cylindrical surfaces, comprising a tubular body, a plurality of abrasive members arranged in an annular row within the body, and means for adjusting said abrasive members radially on said body including oppositely disposed cones arranged on the exterior of said body and movable lengthwise thereof, adjusting plates movable radially on said body and also capable of tilting relative to the axis of the same and each engaging its 25 opposite ends with the opposite ends of one of said abrasive members and also with said oppositely disposed cones, and means for adjusting said cones lengthwise relative to each other.

30. 16. A grinding device for operating on external cylindrical surfaces, comprising a tubular body, a plurality of abrasive members arranged in an annular row within the body, and means for adjusting said abrasive members radially on said body including oppositely disposed cones arranged on the exterior of said body and movable lengthwise thereof, adjusting plates movable radially on said body and also capable of tilting relative to 35 the axis of the same, and each engaging its opposite ends with the opposite ends of one of said abrasive members and also with said oppositely disposed cones, means for adjusting said cones lengthwise relative to each 40 other including a casing which connects with one of said cones and slidably receives the other cone, and an adjusting sleeve engaging the last-mentioned cone and adjustably connected with said casing.

45. 17. A grinding device for operating on external cylindrical surfaces, comprising a tubular body, a plurality of abrasive members arranged in an annular row within the body, and means for adjusting said abrasive members radially on said body including oppositely disposed cones arranged on the exterior of said body and movable lengthwise thereof, adjusting plates movable radially on said body and also capable of tilting relative to 50 the axis of the same and each engaging its opposite ends with the opposite ends of one of said abrasive members and also with said oppositely disposed cones, means for adjusting said cones lengthwise relative to each 55 other including a casing which connects with

one of said cones and slidably receives the other cone, and an adjusting sleeve engaging the last-mentioned cone and adjustably connected with said casing, a pin arranged on the casing and engaging with a longitudinal groove in the last-mentioned cone, and a pin arranged on said body and engaging with a longitudinal opening in said casing. 70

In testimony whereof, I hereby affix my signature.

75 MARSDEN C. HUTTO.
